WALKING BEAM MOUNTING

Filed Dec. 6, 1926

2 Sheets-Sheet 2

UNITED STATES PATENT OFFICE.

WILLIAM CLARKSON, JR., OF CORSICANA, TEXAS.

WALKING-BEAM MOUNTING.

Application filed December 6, 1926. Serial No. 153,029.

This invention relates to new and useful improvements in walking beam mountings.

The object of the invention is to provide a mounting for a walking beam for pumping oil wells, which will be simple in construction, substantial and easy to erect.

A further object of the invention is to provide efficient and adequate braces which will hold the Samson post against swaying and displacement, which will be easy to install and which will not be likely to get out of place.

Another object of the invention is to provide saddle plates which will be substantial and easily installed and rigidly supported.

A still further object is to provide a supporting post mounted and supported in a simple and efficient manner.

Another object of the invention is to provide a brace foot member adjustable with relation to the base of the post for taking up slack and play.

A construction designed to carry out the invention will be hereinafter described, together with other features of the invention.

The invention will be more readily understood from a reading of the following specification and by reference to the accompanying drawings, in which an example of the invention is shown and wherein:

Fig. 1 is a side elevation of a walking beam mounting constructed in accordance with my invention.

Fig. 2 is a vertical sectional view of the Samson post,

Fig. 3 is a cross-sectional view taken on the line 3—3 of Fig. 1,

Fig. 4 is a plan view of the front brace footing.

In the drawings the numeral 10 designates an upright Samson post, which is preferably formed of pipe cut to the proper length, but which may assume any shape consistent with the invention. This post is seated in an annular recess or socket 11 and surrounded by an upstanding annular flange 12 integral with a base plate 13. The base plate is fastened by foot bolts 14 imbedded in a concrete base 15 on which the plate is supported.

At the upper end of the post 10 I mount saddle plates 16 which have their inner sides curved to conform to the contour of the post. These plates are mounted on opposite sides of the post and are secured thereto by bolts

17. Each plate is provided with an inwardly directed shoulder 18 resting on top of the post and taking the downward thrust off of the bolts. Above its shoulder, each plate 16 has a concaved bearing saddle 19 for receiving the transverse fulcrum bar 20 of a walking beam 21. The walking beam is preferably formed of metal members; but its particular construction is not a part of the invention. Each plate 16 is provided with central vertical ears 22 receiving the eyes of inclined brace rods 23. These brace rods may be omitted if desired.

One of the features of the invention resides in brace members applied to the front 70 and rear and one side of the Samson post. As each of these braces is substantially the same in construction, I have designated them by the letters A, B and C and have applied to like parts the same reference numerals. Each brace includes an upper bracket 24 curved to fit the contour of the post 10 and provided with vertical side flanges 25 secured to the post by bolts 26. The bracket includes an angular boss 27 having a lug 28 extending outwardly from its lower end. When the bracket is mounted on the Samson post, the lower face inclines upwardly at an angle to the post. In the bottom of the boss I provide a circular socket 29, as is shown in Fig. 2.

The brace member constitutes a tubular brace or pipe 30 having its upper end seated in the socket 29 and a tension rod 31 extending through the lug 28 and receiving a nut 32 on its upper end. At the lower end of the brace member, I provide a foot member 33, including a horizontal base plate 34 mounted on a sill plate 35 and an upwardly extending boss 36. The boss is provided with a circular socket 37 receiving the lower end of the brace 30, and is also undercut to form a lug 38 through which the rod 31 passes. A nut 39 is screw-threaded on the lower end of the rod and by tightening the nuts 32 and 39 the brace 30 is seated in its sockets, whereby the brace member is tensioned and made rigid.

It is obvious that braces, in order to be effective, must be adjustable so as to take up the slack and play. When the brace 30 is seated in the sockets 29 and 37, the parts are held rigidly by the rod 31, but in order to further brace the Samson post and to straighten it, if necessary, and also to aid in

assembling the brace member, the base 34 is slidable on the sill plate 35. In carrying out this part of the construction, the sill plate is held in position by foot bolts 40 imbedded in the concrete base 15 and extending up through slots 41 in the plate 34. Nuts 42 mounted on the upper ends of said bolts serve to confine the base plate on the sill plate and to fasten the base plate in position.

To adjust the foot member, a tie rod 43 is provided at its inner end with an eye 44 engaged over one of the foot bolts 14 of the Samson post base plate 13. The other 15 end of the rod extends through the boss 36 and is screw-threaded to receive a nut 45, which bears against the outer end of the foot member. It will be seen that by loosening the nuts 42 and turning the nut 45 20 to the left, or removing it if necessary, the foot member can be slid outwardly so that the brace 30 may be stepped into its sockets. Then by replacing the nut 45 and screwing it to the right, or in a clockwise direction, 25 the foot member will be slid inwardly on the plate 35, thus taking up the slack in the brace. The nuts 32 and 39 are, of course, tightened and by properly adjusting the nuts 32, 39, 42 and 45, the brace member 30 may be rigidly positioned and the Samson post firmly held in place.

The brace members A and B, being in line with the walking beam 21, will brace the Samson post against tilting back and forth 35 in the arc of the swing of said beam. The side brace member C will also act as a strut, whereby the post will be braced against tilting to either side. Where the rods 23 are employed, they will, of course, act as additional side braces, and, if necessary, a brace 40 rod 46, including turn-buckle 47, may have its upper end secured to a stud 48 on the side of the Samson post. The lower end of the rod 46 is provided with a head 49 engaged in a housed ear 50 on the base plate 13. The rod 46 is placed on the opposite side from the brace C.

When the beam 21 is not in use, it is customary to provide a support for the same, 50 and, therefore, an upright post 51, known in the oil fields as a "headache" post, is mounted on a flanged base 52, which is secured to the concrete base 15 by foot bolts 53. Side braces 54 may be employed if desired. The upper end of the post 51 is held 55 in place by a reach rod 55 secured to the Samson post.

It is to be understood that any type of walking beam may be mounted in bearing 60 saddles 19. In constructing the parts 10, 30 and 51, what is known as "junk" pipe or tubing may be used, therefore, making for economical construction.

Various changes in the size and shape of 65 the different parts, as well as modifications

and alterations, may be made within the scope of the appended claims.

What I claim, is:

1. In a walking beam mounting, the combination of a base member, a Samson post mounted on the base, saddle plates secured to the upper end of the post, brace brackets fastened to the upper portion of the post on its front and rear sides, a rear brace inclined from the rear bracket, a rear foot 75 member receiving the lower end of the rear brace, a front brace inclined from the front bracket, a front foot member receiving the lower end of the front brace, a tie rod extending from the post base member to the front foot member, and tie rods extending from the brackets down the brace and secured at their lower ends to the front and rear foot members.

2. In a walking beam mounting, the combination of a base member, a Samson post mounted on the base, saddle plates secured to the upper end of the post, brace brackets fastened to the upper portion of the post on its front and rear sides, a rear brace inclined 80 from the rear bracket, a rear foot member receiving the lower end of the rear brace, a front brace inclined from the front bracket, a front foot member receiving the lower end of the front brace, a tie rod extending 85 from the post base member to the front foot member, a side bracket secured to the Samson post, an inclined brace extending from the side bracket, a side foot member receiving the lower end of the side brace, a tie rod 90 extending from the side foot member to the post base member and tie rods extending from each bracket down to each foot member.

3. In a walking beam mounting, the combination of a Samson post, a bracket secured to the post at its upper portion having a socket and a lug, a foot member spaced from the base of the post and having a socket and a lug, a brace member having its upper and lower ends seated in the sockets of the bracket and the foot member, a tie rod extending parallel to the brace having its ends engaging in the lugs, and means for tensioning the tie rod to fasten the brace. 105

4. In a walking beam mounting, the combination of a Samson post, a bracket secured to the post at its upper portion having a socket and a lug, a foot member spaced from the base of the post and having a socket and a lug, a brace member having its upper and lower ends seated in the sockets of the bracket and the foot member, a tie rod extending parallel to the brace having its ends engaging in the lugs, means for tensioning the tie rod to fasten the brace, and a second tie rod extending from the post base to the foot member. 120

In testimony whereof I affix my signature.
WILLIAM CLARKSON, JR.
